FERRAND F. ELLIS, OF ONEIDA, NEW YORK.

LINK-PERFORATING AND CHAIN-FORMING MACHINE.

1,046,060.

Specification of Letters Patent.

Patented Dec. 3, 1912.

Application filed March 9, 1909. Serial No. 482,398.

To all whom it may concern:

Be it known that I, FERRAND F. ELLIS, of Oneida, in the county of Oneida, in the State of New York, have invented new and useful Improvements in Link-Perforating and Chain-Forming Machines, of which the following, taken in connection with the accompanying drawings, is a full, clear, and exact description.

10 This invention relates to certain improvements in link perforating and chain forming machines, by which the flat imperforate sheet metal blanks are automatically perforated, bent and interlinked in succession, 15 one with another to form a chain of any desired length.

The imperforate blanks are cut to the desired form from flat sheet metal and are placed in quantity one upon the other flatwise in a suitable magazine, and are automatically and successively fed one by one between suitable dies which form perforations in the opposite ends of the blanks as they are successively presented thereto, the 25 perforated blank being successively removed from the dies and automatically folded or bent around a forming pin, leaving its perforations in alignment with each other through which the next succeeding perforated blank is threaded and similarly bent around the forming pin, this operation being repeated for each link to form the chain.

The operation of cutting or perforating the blanks by the dies necessarily leaves a 35 slight bur around the edges of each perforation next to the female die, and at the same time slightly rounds the edges of the perforations on the side next to the male die, so that if in bending the perforated blank upon 40 itself to form the link, the burs are exposed on the outer faces of such link, it produces undue abrasion or cutting of the adjacent portions of the links of the chain, and one of the objects of my present invention is to 45 obviate this result by folding or bending the links so that the burs will be at the inside or adjacent faces of each link.

The main object, however, is to automatically perforate, fold and interlink the links 50 one with the other with the least possible mechanism and at the same time to produce a more perfect link and more durable chain with greater speed and economy than has heretofore been practised.

Other objects and uses relating to the 55 specific parts of the machine will be brought out in the following description:

In the drawings—Figure 1 is a top plan of a link perforating and chain forming machine embodying the various features of 60 my invention. Fig. 2 is a front elevation of the same machine, the perforating dies being shown as separated and the previously 65 perforated link as moved from between the dies through one of the previously formed 70 links and about to be rotated a quarter turn for bending around the forming pin. Fig. 3 is an end elevation of the right hand end of the machine shown in Figs. 1 and 2. Fig. 4 is a transverse vertical sectional view 75 taken on line 4—4 Fig. 1. Fig. 5 is a similar transverse vertical sectional view taken on line 5—5 Fig. 1, showing particularly the 80 perforating dies and magazine for the blanks, together with the mechanism for feeding the blanks one by one from the 85 magazine to the dies. Fig. 6 is an enlarged top plan of a portion of the machine showing the slide for feeding the perforated blank from the dies to the link forming 90 mechanism, and also showing the means for turning the link and gripping jaws for bending such link around the forming pin, the magazine with the imperforate blanks 95 therein being shown in section. Fig. 7 is an enlarged sectional view taken on line 7—7 Fig. 6. Fig. 8 is an enlarged detail plan of the rear end of the slide upon which the gripping fingers are mounted and cam for operating said slide and fingers. Fig. 9 100 is a sectional view taken on line 9—9 Fig. 8. Fig. 10 is an enlarged sectional view taken on line 10—10 Fig. 1.

Practically all of the moving parts of this machine are supported directly or indirectly upon a suitable supporting frame 105—1— and derive their motion from a main driving shaft —2— having a pulley —3— adapted to be connected by a belt to any available source of power not shown, said 110 shaft being journaled in suitable bearings —4— on the main frame.

The imperforate metal blanks, as —a— Fig. 6 are stacked one upon the other in a vertical column within an upright guide 105 tube or magazine —5—, the lower one resting upon a horizontal bed or guide plate —6— in the path of one end of a reciproca-

tory feeding bar —7— which is guided against vertical displacement in parallel ways —8—.

The lower end of the magazine —5— rests upon the ways —8— and bridges across the intervening space between said ways and in which the feeding bar —7— is movable, leaving a clearance between the lower end of the magazine —5— and guide plate —6—

10 corresponding to the thickness of one of the blanks and feed bar —7— to permit the latter to pass through such clearance and thereby feed the lowermost blank from the magazine to a position between suitable perforating dies —9— and —10— which are located just at the rear of the magazine —5—.

The lower female die —9— is preferably made separate from the frame but is stationarily seated in a recess —11— in a portion thereof with its upper face in a plane

20 substantially coincident with that of the plate —6— and forms a continuation of said plate for supporting the blank. This female die —9— is provided with a pair of apertures —12— extending therethrough from top to bottom in alinement with an underlying opening —13— in the top of the frame or bed —1—, the latter opening serving as a convenient outlet for the portions of the 25 blank which are cut out by the male die —10—, the die —9— being usually made of hardened steel and may be removed when worn or otherwise impaired and replaced by a new one.

30 The male dies —10— are secured in the lower end of a vertically reciprocating plunger —14—, and are movable into and out of the upper ends of the apertures —12— in the female die with which they register, bearing substantially the same cross sectional area as their corresponding apertures —12— for punching out portions of the opposite ends of the blanks —a— as the latter are successively fed between the dies, thereby

45 leaving each blank with a pair of similar perforations which are adapted to be brought into alinement as the flat link is folded around the forming pin in the manner hereinafter described.

50 A horizontal feed bar —15— is reciprocated along suitable ways —16— in the upper portion of the frame —1— at right angles to, and in the same plane as that of the feed bar —7— and just at the rear of the 55 plane of movement of the dies —10—, and serves as a limiting stop or abutment against which the imperforate blank is fed and temporarily held by the feed bar —7— during the operation of perforating the blank. As

60 the bar —15— is moved inwardly into position to be engaged by the blank it also operates to feed the previously perforated blank into position to be folded or bent around the forming pin by the gripping jaws hereinafter described, so that it per-

forms the double function of a limiting stop and feed bar. The feed bar —7— is moved inwardly intermittently step by step, a part of such movement serving to feed the lowermost blank from the magazine —5— against the front edge of the bar —15— or directly between the dies —9— and —10—, whereupon the plunger —14— is depressed to force the dies —10— through the underlying blank for perforating the latter. As soon as the blank is perforated the plunger —14— and dies —10— are withdrawn upwardly and the bar —15— is also withdrawn to the left out of engagement with the perforated blank, whereupon said blank is fed rearwardly into the path of movement of the bar —15— by the additional rearward movement of the feed bar —7—, as will be more clearly pointed out in the following description.

Mechanism for feeding the blanks from the magazine to the perforating dies.—Secured to the main shaft —2— is a cam disk —17— having substantially half of its periphery concentric with its axis and the remaining half provided with a quick throw cam portion —18— and a comparatively short depression —19—. A forwardly and rearwardly extending lever —20— has its rear end bifurcated or slotted and saddled upon the shaft —2— to slide transversely thereof, and its front end is pivotally connected to an upright rock arm —21— having its upper end secured to a rock shaft —22— having an arm —21'— connected by a link —23— to the sliding feed plate —7—. Mounted upon the rear end of the lever —20— in front of the shaft —2— is a roller or stud —24— which is held against the periphery of the disk —17— by a spring —25— acting upon the lever —20—, said spring having one end connected to the rear end of said lever and its opposite end connected to a bracket —26— on the main supporting frame and, therefore, normally tends to draw the lever —20— rearwardly, thereby holding the roller or stud —24— in contact with the periphery of the disk —17—. The cam disk —17— is shown in Fig. 5 in position to engage the advance end of its concentric periphery with the roller, in which position the feed plate —7— is forced inwardly a sufficient distance to feed the link blank between the dies ready to be perforated, and is allowed to remain in this position by the concentric portion of the disk —17— during the perforating operation of the plunger —14— and return thereof to its starting position, and also during the withdrawal of the feed bar —15— from the rear of the now perforated link. By the time the bar —15— is withdrawn in the manner just described, the disk —17— will have advanced practically a half revolution, whereupon the depression —19— will have 130

been presented to the roller —24— allowing the latter to enter said depression and thereby permitting the spring —25— to draw the lever —20— and feed plate —7— connected thereto still farther rearwardly until the perforated link blank is brought into the path of movement of the feeding bar —15—. This second movement of the feeding plate —7— is only momentary by reason of the comparatively short length of the depression, whereupon the eccentric portion —18— of the cam disk —17— engaging the roller —24— immediately and quickly returns the feeding plate —7— forwardly to its starting position ready to repeat the operation of feeding the next lower blank to the perforating dies.

Mechanism for operating the perforating plunger.—This mechanism comprises a rotary cam disk —27— and a lever —28—, the disk —27— being secured to the main shaft —2— and provided on its periphery with a cam tooth —29—, the greater portion of the periphery of the disk being concentric with its axis. The lever —28— is pivoted intermediate its ends at —30— upon an upright bracket —31— of the main frame, and is provided at its rear end with a roller or stud —32— bearing upon the periphery of the disk —27—, the front end of the lever being provided with rounding bearing faces seated in an opening —33— in the plunger —14—. Pivotaly connected to the rear end of the lever —28— is a pendant arm —35— having its lower end bifurcated and embracing the shaft —2— to move transversely thereof, and its intermediate portion provided with a stud or roller —36— which enters a cam recess —37— in one side of the disk —27—, said recess corresponding in shape somewhat to the periphery of the disk —27—, that is, a portion of the recess —37— in radial alinement with the cam tooth —29— is extended radially toward said cam tooth to allow the roller —36— to enter said radial extension as the roller —32— rides upon the tooth —29—, the rear side of the extension of the recess —37— serving to engage the roller —36— and thereby positively depress the rear end of the lever —28— to correspondingly elevate the plunger —14— as the roller —32— rides down the rear side of the cam tooth —29—. It is now clear that the lever —28— and plunger —14— are operated in both directions positively by the cams of the disk —27—, the positive upward movement of the plunger being necessitated by reason of the fact that the dies tend to stick in the perforations formed thereby in the metal blank, while the blank is held against upward movement between the feed bars —7— and —15—.

The means for feeding the perforated blanks from the dies to the forming mechanism comprises the sliding bar —15—, a

lever —38— and a cam —39—, the lever —38— being pivoted intermediate its ends at —40— and has its front end provided with an elongated slot —41— for receiving a pin —42— on the sliding bar —15—. The rear end of this lever —38— is provided with a stud —43— which is held against a spiral face —44— by a spring —45— the latter having one end connected with lever —38— and its opposite end connected to a fixed anchorage —46— on the main supporting frame, and constitutes the means by which the lever —38— is rocked to move the sliding bar —15— inwardly toward the dies. The cam —39— is rigidly secured to the main driving shaft —2— and its cam face —44— is preferably spiral shape with the high and low points at diametrically opposite sides of the axis and representing the extreme throw of the cam to move the sliding plate —15— from one extreme to the other extreme position. In some instances it may be desired to vary the degree of movement of the bar —15— and for this purpose I have provided an adjustable screw stop —47— which is movable in a threaded aperture in a boss —48— on the main frame and engages one side of the lever —38— to limit its action by the spring —45—.

Link bending and chain forming mechanism.—This mechanism comprises a forming pin —50—, a pair of gripping jaws —51— and a link turning head —52— in combination with suitable operating mechanism hereinafter described. The forming pin —50— is preferably cylindrical at its upper end with the exception that it is provided with a lengthwise slot —54— for receiving the ends of the transversely formed link, while the next succeeding link is being formed around the pin in order to preserve the circular form of the eye of the link. This forming pin or rod is movable vertically in a tubular guide —50'— to withdraw its upper end from each link after the latter has been bent around said pin and allow the jaws to draw the formed link backwardly in position to receive the next succeeding link.

The means for reciprocating the forming pin —50— preferably consists of a pair of similar levers —55— and a pair of like cams —56— which latter are mounted upon and rotated with the main driving shaft —2— as best seen in Fig. 4. The levers —55— are secured at their rear ends to a rock shaft —57— and are provided with upwardly projecting arms —55'— having their upper ends spring-pressed against the peripheries of the cams —56— by tension springs —58—. As previously stated, the cams —56— are identical and are arranged in the same relative position upon the shaft —2— substantially half of each cam being of greater radius than that of the oppo-

site half, although the greater portion of the periphery of each half is concentric with the axis of revolution so that the forming pin is held in its extreme upper position during substantially half a revolution of the main shaft and is either in its full or partly depressed position during the remaining half revolution of said shaft. The jaws —51— are mounted upon the front ends of opposite similar levers —60— which are fulcrumed intermediate their ends —61— upon a sliding support —62—, the latter being provided at its rear end with an inclined face —63— upon which rests a vertically adjustable contact member —64— adapted to be engaged by the periphery of a cam —65— on the main driving shaft —2—. The contact member —64— is adapted to be adjusted vertically along the incline —63— by a cap screw —66— which is tapped into the rear end of the sliding bar —62—, the object of the adjustable contact member —64— being to adjust the jaws —51— relatively to the forming pin so that they will co-act with said pin to properly bend the ends of the link around the same. It is now apparent that the levers —60— and jaws —51— thereon are rockable toward and from each other, and are also movable bodily back and forth toward and from the forming pin —50—, being guided in their reciprocatory movement upon a suitable guide block —67— on the main supporting frame —1—, as best seen in Figs. 4, 8 and 9.

The radii of diametrically opposite portions of the cam disk —65— are unequal but the periphery of each half is substantially concentric with the axis, thereby holding the jaws —51— in each extreme position during substantially half a revolution of the main driving shaft. The rear ends of the levers —60— extend a short distance beyond the inner periphery of the cam —65— and engage opposite faces of said cam. A portion —70— of the cam —65— is somewhat thinner than the remaining portions forming opposite pairs of beveled shoulders —71—, the thinner portion —70— being substantially equal to one quarter of the cam and is located at the advance end of the portion of the cam of greatest radius. The rear ends of the levers —60— are connected by a spring —73— which operates to hold the rear extremities of the ends of the levers with opposite faces of the cam —65— and tends to open the jaws —51—, especially when the rear ends of the levers are in contact with the thinner portion —70—. It is now apparent that the jaws —51— will begin to open at about the same time that they begin to move forwardly, the object of this being to permit the jaws to engage the ends of the link and fold them around the forming pin. Just prior to this latter

action, however, the perforated link which has been previously fed into engagement with the slotted end of the head —52— is turned a quarter turn in the direction indicated by arrow "Y", Fig. 1, thereby presenting the link flatwise to the forming pin so that when the jaws —51— are advanced or moved forwardly in their open positions, they will fold the ends of the link around said forming pin and while in this position the rear shoulders —71— will act upon the rear ends of the levers to spread them apart and thereby force the front ends of the jaws firmly against the opposite sides of the links and press the forwardly projecting ends of said link firmly together with their apertures in alignment.

It will be observed that by turning the head —52— in the direction indicated by arrow "Y" the bottom portions of the links in which the burs are formed by the perforating dies will be brought against the forming pin and when folded around said forming pin will bring the burs at the inside of the folded ends of the link, thereby leaving the outer surfaces of the link smooth and slightly rounded at the corners to prevent undue abrasion of the links one upon the other by the burs. As soon as the link is bent around the forming pin in the manner just described, said forming pin is withdrawn downwardly from the link and the jaws are then moved rearwardly carrying the formed link with them into alignment with the feeding bar —15—, which latter is now operated to feed the next perforated link through the aligned apertures in the previously formed link and into engagement with the slotted end of the head —52—, as best seen in Fig. 6. As soon as the advance end is properly seated in the head —52— the latter is turned a quarter turn, as previously stated, and the forming pin —50— is elevated to its operative position, allowing the forward ends of the previously formed link to enter the slot —54— in said forming pin, whereupon the jaws —51— are advanced in the manner described to bend the succeeding link around the forming pin, these operations being repeated as each link is fed to the perforating dies and perforated. The head —52— is mounted on the inner end of a rock shaft —76—, which in turn is secured within a rocking sleeve —77—, the latter being journaled and movable endwise in suitable bearings —78—, as best seen in Fig. 7, and is provided with annular shoulders or collars —79— spaced apart for receiving between them a stud or roller —80—, this roller being mounted on one end of a horizontal lever —81— which is fulcrumed intermediate its ends —82— and is provided at its rear end with a stud —83— bearing against a cam face —84— on the main shaft —2—. The stud —83— is held against the

cam face —84— by a spring —86— connecting the rear end of the lever with a suitable anchorage —87—, as best seen in Fig. 1.

The means for rocking the sleeve —77— and head —52— carried thereby consist of a cam —88— and lever —89—, the latter being connected at its front end to a crank arm —90— on the outer end of the sleeve —77— while the rear end of said lever is bifurcated and saddled upon the shaft —2— and is provided with a stud or roller —91— riding against the face of the cam —88—. The throw of the cam —88— is adjusted to move the crank arm —90— and parts connected thereto through substantially quarter of a revolution to bring the perforated link about to be formed from a flat, horizontal position to an edgewise vertical position. The stud or roller —91— is held against the periphery of the cam —88— by a spring —92— which connects the rear end of the lever —91— to a fixed anchorage —93—, as best seen in Fig. 3. The hub of the crank arm —90— is feathered upon the shaft and is provided with an annular groove —95— for receiving a forked portion of an arm —96—, the latter being secured to the frame —1— and serves to hold the crank arm against axial movement as the sleeve —77— is moved back and forth therethrough and at the same time allow said crank arm to be rocked on its axis for similarly rocking the sleeve —77— and head —52—.

The operation of my invention briefly described is as follows: In cutting the blanks burs will unavoidably be formed upon one side, and these blanks are delivered by suitable mechanism, not shown, into the magazine —1— with the burs at the bottom. The lowermost blanks in the magazine —5— gravitate from the bottom of the magazine —5— onto the underlying plate or table —6— and are successively forced by the feed plate —7— between the dies —9— and —10—, the feeding bar —15— being previously advanced across the back edge of the link. These feeding plates —6— and —15— remain in this position to hold the link in proper registration with the dies during the descent of the plunger —14— by which the opposite ends of the blank are perforated, said plunger being quickly depressed and withdrawn, and as soon as the die —10— is drawn out of the apertures formed thereby, the feed bar —15— is withdrawn from behind the perforated link, whereupon the feed plate —7— is moved still further rearwardly to feed the perforated link into the path of the movement of the feed bar —15—. As soon as this latter operation takes place, the bar —15— is actuated to feed the perforated link behind the forming pin and into interlocking engagement with the head —52—, during which operation the feed plate —7— is re-

turned to its starting position to feed the next blank to the perforating dies. As soon as the perforated blank is fed to the interlocking engagement with the head —52—, the latter, together with the link, is turned a quarter of a revolution to bring the under side of the link having the burs thereon into upright position facing the forming pin which is now in its extreme upward position. As soon as the link is turned upon its edge, the head —52— is withdrawn from interlocking engagement therewith and the jaws —51— are immediately advanced to press the ends of the link around the forming pin —50— and are then closed upon the forming pin and link to impress the perforated ends of the link close together, and after a brief interval of time during which the form of the link sets to maintain its shape, the forming pin is withdrawn downwardly and the gripping jaws with the formed link therein are then withdrawn rearwardly a sufficient distance to bring its apertures into alinement with the next advancing perforated link, as fed laterally by the feeding bar —15—, said successive link being, therefore, passed through the apertures of the previously formed link and is interlocked with the turning head —52— in the manner previously described, whereupon the forming pin is again elevated, causing the front ends of the previously formed link to enter the slot in the rear face of said forming pin and allowing the perforated blank which has just been passed through the previously formed link, to be turned edgewise vertically and pressed or bent by the forward movement of the jaws —51— around the forming pin in the same manner as previously described. These several operations are continued in the order specified, being controlled by their respective cams and connections to form the chain.

In cutting the blanks and perforating them in the manner described the burs will be formed at the corners on one side of the perforating blank, while the opposite corners will be more or less rounding, so that when the link is folded around the forming pin with the burs at the inside, the outer corners will be smooth and slightly rounding thereby avoiding undue abrasion or cutting of the links one upon the other by the burs and rendering the swivel action of the links easier one upon the other.

What I claim is:

1. In a link perforating and chain forming machine, a magazine in which the imperforate metal blanks are stacked one upon the other, mechanism for perforating the blanks, means for feeding the blanks one by one from said magazine to the perforating mechanism, a link forming mechanism comprising a reciprocatory forming pin and reciprocatory jaws for engaging and bending

the ends of the link around the forming pin, and mechanisms for feeding the perforated blanks from the perforating mechanism to the forming mechanism, whereby when the 5 blanks are bent around the forming pins the bur sides will be brought together.

2. In a link perforating and chain forming machine, a magazine in which the imperforate blanks are stacked one upon the 10 other, a perforating mechanism, automatic means for feeding the blanks one by one from the magazine to the perforating mechanism, a link forming mechanism comprising a forming pin and jaws movable toward and from the forming pin, and means for 15 feeding the perforated blanks from the perforating mechanism between the jaws and forming pin of the forming mechanism.

3. In a link perforating and chain forming machine, a magazine in which the imperforate blanks are stacked one upon the other, a perforating mechanism, a slide-plate movable back and forth under the lower end of the magazine and feeding the 20 lowermost blanks one by one from the magazine to the perforating mechanism, said slide-plate having an additional movement to feed the perforated blank from between the perforating dies after the same 25 has been perforated, a link bending and forming mechanism comprising a forming pin and reciprocatory jaws movable toward and from the forming pin, and an additional slide-plate for feeding the perforated blanks 30 between the forming pin and jaws.

4. In a link perforating and chain forming machine, a perforating mechanism comprising male and female dies, one of said dies being movable toward and from the 40 other, a slide bar movable back and forth at one side of the perforating member of the dies, a slide-plate movable at right angles to and in the same plane as the sliding bar, means for feeding the blanks one by one 45 into the path of movement of the plate, said plate engaging and moving the blank between the perforating dies and against the sliding bar to hold said blank in position during the perforating operation, the plate 50 having an additional movement for feeding the perforated blank into the path of movement of the bar after the latter has been withdrawn from its holding position, a link bending and chain forming mechanism at 55 one side of the dies and comprising a forming pin and jaws movable toward and from the forming pin, the bar operating to feed the perforated link between the forming pin and jaws and mechanism for reciprocating 60 said bar and plate.

5. In a link perforating and chain forming machine, a link perforating mechanism comprising male and female dies, one of which is movable toward and from the other, 65 a sliding member movable toward and from

the dies to feed the blanks one by one between said dies, a chute for guiding the imperforate link blanks one by one into the path of movement of said sliding member, a second sliding member movable back and forth across the plane of movement of the first sliding member, and a link bending and chain forming mechanism comprising a forming pin and jaws movable toward and from the forming pin, said second sliding member 70 engaging and feeding the perforated blank in the path thereof between the forming pin and jaws and mechanisms for operating the sliding members.

6. In a link perforating and chain forming machine, a perforating mechanism comprising male and female dies, one of which is movable toward and from the other to perforate the link blank, a sliding member movable toward and from and in a plane 80 between the adjacent faces of said dies when the latter are separated, a second sliding member movable in said plane across the line of movement of the first named sliding member, said sliding members constituting 85 means to engage and hold the link blank during the perforating operation, the first named sliding plate having an additional movement after such perforating operation to feed the perforated blank into the path of 90 the movement of the second sliding member when the latter is withdrawn from its holding position, means comprising a forming pin and jaws movable toward and away from said pin for bending the perforated 95 blank around the forming pin, and mechanical means for arranging the link with its bur side adjacent to the forming pin before bending, said second sliding member operating to feed the perforated blank in the 100 path thereof through the perforations of the previously formed link while held in the jaws.

7. In a link perforating and chain forming machine, vertically disposed dies, means for feeding the link blanks one by one in a horizontal position between the dies, means for reciprocating one of the dies to perforate the blank, a vertically disposed forming pin at one side of the dies, mechanism 110 for feeding the perforated blank from between the dies to the forming pin and additional mechanism for turning such blank from a horizontal to a vertical position with its bur side toward the pin, and additional 115 mechanism for bending the perforated blank around the forming pin.

8. In a link perforating and chain forming machine, vertically disposed dies, means for feeding the link blanks one by one in a horizontal position between the dies, means for reciprocating one of the dies to perforate the blank, a vertically disposed forming pin at one side of the dies, mechanism 125 for feeding the perforated blank from be- 130

tween the dies to the forming pin and additional mechanism for turning such blank from a horizontal to a vertical position with its bur side toward the pin, additional mechanism for bending the perforated blank around the forming pin, additional means for withdrawing the forming pin from the bent link, and further means for shifting the bent link to bring its perforations into

position for receiving the next succeeding 10 link.

In witness whereof I have hereunto set my hand.
